UNITED STATES PATENT OFFICE.

CONSTANTIN VON GÖRTZ, OF VIENNA, AUSTRIA-HUNGARY, ASSIGNOR TO
THE FIRM OF SKODAWERKE ACTIENGESSELLSCHAFT IN PILSEN, OF PIL-
SEN, AUSTRIA-HUNGARY.

PRIMER FOR ORDNANCE.

SPECIFICATION forming part of Letters Patent No. 694,265, dated February 25, 1902.
Application filed September 28, 1900. Serial No. 31,428. (No model.)

To all whom it may concern:

Be it known that I, CONSTANTIN VON GÖRTZ, a subject of the Emperor of Austria-Hungary, residing at Vienna, in the Province of Lower Austria, in the Empire of Austria-Hungary, have invented certain new and useful Improvements in Primers for Ordnance; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In order to combine certainty of firing with the advantages of electrical primers for ordnances it is necessary for an electrical primer to be such that in case of a failure of the electrical firing the charge can be fired immediately mechanically by percussion without changing any part. When metal cartridge-cases are used, this object can be described in combination with an arrangement on the breech-block of the gun comprising 20 an electrical conductor which is insulated from the breech-block and leads to a contact-piece of the primer and a firing-pin, which is arranged in the breech-block for percussion firing.

25 Referring to the drawings, in which like parts are similarly designated, Figure 1 is a section of the primer, and Fig. 2 is a similar section showing parts of a gun and shell.

The percussion firing arrangement of the primer comprises a body *a*, of brass or steel, a cap *b*, and an anvil *c*, having a central opening *c'*, filled with the priming composition, and a detonating charge *e*, placed in the end of the body *a*. The anvil is threaded and secured into the body *a*. In Fig. 2 the primer is shown inserted in the end of a cartridge *k* in a gun whose breech-block *m* contains a suitable opening *l* and a firing-pin *p*, propelled by a spring *r* and suitably guided 40 in the breech-block. By releasing the firing-pin *p* it will be driven by its spring *r* into the opening *l* against the head of the body *a* of the primer to strike the cap *b* between the head and the anvil *c* against the anvil to dis-

charge the cartridge in the usual way. For 50 firing by electricity the following additional mechanism is required: A conducting-wire *f*, inserted in and insulated from the primer and here shown as located in a groove cut in the base of the screw-thread of the primer-body, one end passing through a radial hole to the interior of the primer-body and connected to an incandescent wire *g*, located in the primer body and within the priming composition *d* and finally terminating at *g'*, the 55 exterior wall of the primer, and forming, preferably, though not necessarily, a contact with the cartridge-shell *k* or secured to the body of the primer. The other end of the wire *f* passes through the base of the primer and is 60 insulated therefrom and is formed into a suitable contact-button *h*, which is also insulated from the primer by the sleeve *i*. The base of the primer, excepting the button *h*, is covered with a suitable insulating-layer.

The breech-block is provided at or near its contacting surface with the primer with a recess, into which is screwed an insulating-sleeve *m'*, and in this sleeve *m'* is screwed one, *m''*, of conducting material, against a ring-terminal *h'*, insulated by a ring *h''* from the breech-block. From the ring-terminal *h'* leads a suitable insulated wire *o* to one pole of a battery *q* or other source of electricity. The other pole of the battery is in electrical 80 contact with the cartridge-shell, and the connection contains a suitable circuit maker or button *t*. To fire by electricity, it will be only necessary to depress the key or button *t* and circuit will be made through the shell *k*, body 85 *a* of the primer, the incandescent wire *g*, wire *f*, contact *h*, sleeve *m''*, contact-ring *h'*, wire *o* back to battery *q*, thereby heating the wire *g* to discharge the cartridge.

Having thus described my invention, what 90 I claim as new therein, and desire to secure by Letters Patent, is—

1. The combination with a metallic shell having a recess, of a primer comprising a body portion provided with a groove, a conducting-wire in said groove and terminating inside the primer; an incandescent wire inside the primer and connected at one end to the primer.

body and at the other to said insulated wire, and an insulated contact in the head of the primer connected to said insulated wire.

2. The combination with a metallic shell having a threaded recess, of a threaded primer screwed in said recess and provided with a groove cut at the base of the threads of the primer, an insulated metallic contact in the head of the primer, a conducting-wire connected thereto and placed in said groove and terminating inside the primer, an incandescent wire connected to the end of the latter and to the primer-body, an anvil in the primer and a percussion-cap between the anvil and the head of the primer, substantially as described.

3. The combination with a metallic shell having a recess, of a primer adapted to be fired by electricity and by percussion, having

a solid end wall and an exterior thread, a percussion-cap in the primer, an anvil screwed thereon to hold the cap against the end wall, an insulated conducting-wire at the base of the exterior thread, an incandescent wire inside the primer and connected at one end to the insulated wire and at the other to the body of the primer, an insulated contact in the head of the primer connected to said insulated wire and a priming charge surrounding the incandescent wire, substantially as described.

In testimony that I claim the foregoing as my invention I have signed my name in presence of two subscribing witnesses.

CONSTANTIN VON GÖRTZ.
